tion, a corporation of New York

Filed Oct. 26, 1966, Ser. No. 589,615

4 Claims. (Cl. 166—11)

This invention relates to recovering hydrocarbons from a subterranean formation. More particularly, it relates to an in situ combustion method for hydrocarbon recovery.

Many a subterranean formation contains viscous hydrocarbons not readily produced by primary recovery methods. These methods require hydrocarbons movable through the formation by natural reservoir forces in sufficient amounts to be produced commercially from wells by pumping or other fluid lifting means. With secondary recovery methods, external energy is supplied to the fluids in a formation to facilitate their movement to production wells. One useful secondary recovery method employs the in situ combustion of in place combustibles, to provide heat and to increase fluid pressures, as the external energy needed to flow viscous hydrocarbons through the formation into production wells.

There are problems with using in situ combustion in a secondary recovery method for a thick formation which contains viscous hydrocarbons that do not flow under natural formation forces. Under certain conditions, a direct combustion front can suffer from a liquid block which effectively shuts off the cocurrent flow of combustion-supporting gases required to maintain such front. Inverse, or reverse, combustion fronts can be employed to avoid some liquid blocking difficulties. However, excessive amounts of in place hydrocarbons are consumed by the reverse combustion front. Also, production wells are subjected to destructive temperatures and corrosive gases which begin to reduce seriously their useful lives from the moment such reverse front originates. The direct and reverse combustion fronts may be combined into an in situ combustion recovery method. However, known methods using such combined fronts have not provided what we consider to be a satisfactory mode of operation and result.

It is therefore an object of this invention to provide a method for recovering viscous hydrocarbons from a thick formation which overcomes the above-stated problems and difficulties. Another object of this method is subterranean heating of a thick formation by successive counterdirectionally moving combustion fronts whose movement is arranged to be cooperative with gravity drainage of in place fluids to provide for the effective recovery of viscous hydrocarbons. Another object is to control fluid flows in this method by regulating the movement of direct and reverse combustion fronts to avoid liquid blocks, enhance gravity drainage and simplify well operations without sacrificing the improved recovery of viscous hydrocarbons. These and other objects will be apparent when considered in conjunction with the following detailed description of a preferred embodiment of the method of this invention, the claims, and the appended drawings, wherein:

FIGURE 1 is a vertical section of a subterranean formation containing viscous hydrocarbons after practice of initial steps of this invention; and

FIGURE 2 is an illustration of the arrangement of FIGURE 1 during the practice of latter steps of this invention.

In accordance with this invention, there is provided a method for recovering viscous hydrocarbons from a thick formation. Initial steps are practiced through spaced-

2

apart injection and production wells penetrating into the formation whereby a heated zone is produced, by reverse combustion, extending from the production well toward the injection well in the upper portion of the formation.

5 As as result, heat is concentrated about the production well. Thereafter, a direct combustion front is established vertically through the formation adjacent the injection well. This front is moved toward the production well. Selectively placed fractures are used with the reverse and direct combustion fronts in a cooperative manner so that gravity drainage, and thermally stimulated, flows of the viscous hydrocarbons are directed in a substantially uniform manner toward the production well which accepts fluid flows from the lower part of the formation. Hydrocarbons are recovered with this flow of fluid from the production well.

In the drawings and the following description, corresponding structures will be designated with the same nomenclature and numeral.

20 Referring to FIGURE 1 of the drawings, a description of the preferred embodiment of the method of this invention will be given in reference to a subterranean formation 11 which contains viscous hydrocarbons that cannot be readily produced by primary recovery methods. The 25 formation 11 resides beneath the earth's surface 12 between an overburden strata 13 and supporting strata 14. For purposes of this invention, the strata 13 and 14 may be considered to be impervious to fluid flows and barren of hydrocarbons.

30 The formation 11 preferably has no significant horizontal barriers which limit vertical fluid flows. Particularly, the formation 11 should be free of shale, silt stone, and other types of horizontally disposed barriers, which disrupt vertical fluid flows. Also, the formation 11 should be of a relatively great thickness, and preferably the thickness is 40 feet or greater. In any event, the formation 11 should have sufficient thickness that the effects of gravity flow on heat-thinned hydrocarbons are significant when compared to hydrocarbon flows over the distance 40 between the wells employed in this method for producing these hydrocarbons. The formation 11 is exemplified in its desired characteristics for practicing this method by the oil sands of the Athabasca River deposit, and the heavy oil sands of California wherein in situ combustion 45 is presently being employed as a means for the production of petroleum.

As a first step of the present method, well means are provided for conveying fluids between the earth's surface 12 and into the formation 11. The well means may be provided by injection and production wells 16 and 17, respectively, penetrating the formation 11. The wells 16 and 17 are spaced apart at least the thickness of the formation 11. The injection well 16 extends through the entire thickness of the formation 11 to terminate in a fluid-seal on the strata 14. The well 16 includes a casing 18 cemented by a cement bond 19 to the adjacent strata 13 and formation 11. The casing 18 carries a wellhead assembly 21 through which passes a conduit 22 for conveying fluids between the earth's surface 12 and the interior of the well 16. The production well 17 is arranged within the formation 11 so that fluid flows may be taken initially only from the upper half of the formation 11. As illustrated in FIGURE 1, the well 17 penetrates only the upper half of the formation 11 during practice of the initial steps of this method. The well 17 has a casing 23 extending into the formation 11. The casing 23 obtains fluid communication with the formation 11 via a plurality of perforations 24. The casing 23 is sealed by a cement bond 26 to the strata 13. A plug 27 seals the bottom of the casing 23 to fluid flows. Wellhead assembly 28 resides at the upper end of the casing 23. A conduit 29 for con-

veying fluids between the earth's surface 12 and the formation 11 extends through the wellhead assembly 28.

As the next step, a fluid-entry is provided from the well 16 into the upper half of the formation 11. The fluid-entry may be a horizontal fracture extending from an opening in the casing 18 and cement bond 19. For this purpose, the casing 18 and cement bond 19 are notched circumferentially in the horizontal by suitable procedures, for example, as is shown in U.S. Patent 3,050,122. After notching the well 16, a horizontal fracture 33 is extended therefrom at the level of the notch substantially across the formation 11 to a position spaced from the production well 17. Any means for providing the horizontal fracture 33 may be employed. For example, a fracturing fluid can be pressurized through the conduit 22 into the well 16 until the resultant fluid pressures cause the formation 11 to fracture horizontally at the level wherein the casing 18 and cement bond 19 are notched. Other means of providing the fracture 33 may be used if desired. In many cases, the fracture 33 will serve as a fluid-entry extending from the injection well 16 without being held open. However, better results can be obtained by filling the fracture 33 with a propping material 34 to facilitate sustained fluid flows therethrough.

The fracture 33 is spaced at its closest extremity a sufficient distance from the production well 17 that a reverse combustion front created adjacent thereto can expand through the vertical extent of the upper half of formation 11 by the time this front has reached the fracture 33. In practical operations, the fracture 33 will extend from the well 16 about 50-75 percent of the distance to the production well 17. This range of horizontal extensions of the fracture 33, in most instances, obtains the aforementioned vertical expansion of the reverse combustion front moving from the production well 17 toward the injection well 16. For maximum heating and gravity flow of fluids, the fracture 33 is preferably placed at a level spaced a distance one-fourth the thickness of the formation 11 from its upper boundary.

As the next step, a combustion front is established vertically across the upper half of the formation 11 adjacent the production well 17. Any suitable means for obtaining such front may be used. For example, a combustion-supporting gas is introduced, under sufficient pressure, into the conduit 22 of the injection well 16 to flow through the fracture 33, the intervening formation 11, and through the perforations 24 into the production well 17. The formation 11 adjacent the perforations 24 at the well 17 is then ignited by a heating means to produce the reverse combustion front.

Alternatively, after fluid communication is established between the wells 16 and 17, combustion-supporting gas may be flowed temporarily through the conduit 29 of the production well 17. Then the formation 11 adjacent the perforations 24 is ignited by suitable means to form a direct combustion front across the vertical extent of the upper half of the formation 11. Immediately thereafter, the combustion-supporting gas is passed solely from the injection well 16 to the production well 17 to convert the direct combustion front into a reverse combustion front with the combustion products being produced from conduit 29 in the production well 17.

The reverse combustion front is moved, by continued passage of the combustion-supporting gas, from the production well 17 toward the injection well 16 until the front extends at least the vertical extent of the upper half of the formation 11 and also extends horizontally to adjacent the closest extremity of the fracture 33. However, the front may be moved until it extends substantially across the formation 11 between the wells 16 and 17 with a corresponding increased consumption of hydrocarbons.

During the time the reverse combustion front is moving from the production well 17, fluids are removed through this well solely from the upper half of the forma-

tion 11, as was mentioned earlier. The foregoing steps provide for the production of a heated zone 36 (denoted by shading) in the formation 11 adjacent the well 17 in which the hydrocarbons are heated sufficiently that no liquid blocks occur and gravity drainage is enhanced.

The production well 17, for carrying out the foregoing steps, may be of simple and inexpensive design. This construction is of advantage since the well 17 is subject to severe corrosive and thermal attack from the heated fluids produced by the reverse combustion front. In many instances, the lower perforated extremity of the casing 23 in the well 17 will be destroyed in carrying out the reverse combustion front which provides the heated zone 36 but only after it has served its needed purpose. The simple design for the well 17 is further facilitated by the production of a mixture of liquids and gases in the conduit 29. This combined fluid stream allows the use of a single conductor for removing fluids from the well 17.

The concentration of heat in the heated zone 36, especially closely adjacent the production well 17 is of significant advantage. The heat conducted, from the heated zone 36, to the lower portion of the formation 11 permits more ready fluid flows therethrough. In the remaining steps hereinafter described, the hydrocarbons in the heated zone 36 readily flow by gravity to the lower extremities of the formation 11. Thus, the viscous hydrocarbons, in the formation 11 adjacent the production well 17, are placed into a condition of flowing more easily than those more closely adjacent the injection well 16. This condition results in a more uniform sweeping of the formation 11, by the subsequent steps of this invention, for producing a large portion of the hydrocarbons in the formation 11 between these wells.

The well 17 is now arranged, as illustrated in FIGURE 2, for fluid communication solely with the lower half of the formation 11. Any suitable structures may be used for this result. For example, an interliner 38 is disposed within, and fluidly sealed, at its upper extremity to the casing 23. Usually, various types of hangers are used for this construction which are well known to those skilled in the art but not shown in the present drawings, or described in the description, of this method. The interliner 38 is sealed against fluid leakage on top of the strata 14. The cement bond 26 is then extended the full depth of the formation 11. Similarly, the conduit 29 is extended into the lower extremities of the production well 17.

After the well 17 has been arranged to accept fluids only from the lower portion of the formation 11, a fluid-entry is provided into the lower half of the formation 11. For this purpose, a circular notch in the horizontal is formed in the well 17 at its lower extremity. Preferably, the notch is at, or closely adjacent, the lower bedding plane of the formation 11. Thereafter, by suitable means, a horizontal fracture 39 is extended at the level of the notch through the formation 11 toward the production well 17. The same, or different, means may be employed for producing the fracture 39 as were employed in providing the fracture 33. The fracture 39 extends horizontally in the formation 11, at the desired level, so as to reside not closer at any location in the formation to the fracture 33 than the distance d which is less than about three-fourths the thickness of the formation 11. Furthermore, the fracture 39 should extend from the production well 17 toward the injection well 16 so as to reside not closer at any location to any fluid-entry into the formation 11 from the injection well 16 a distance d' which is defined by the following Equations 1 and 2:

$$d' = d \quad (1)$$

wherein $k_v = k_h$, and

$$d' = d \times \frac{K_h}{K_v} \quad (2)$$

wherein $K_h > K_v$

75 In the equations, K_v is the permeability to fluids in the ver-

tical and K_h is the permeability to fluids in the horizontal in the formation 11. By this means of spacing the fracture 39 from the fracture 33, and also any other fluid-entry from the well 16, the problem of premature breakthrough of fluid flows effected from the well 16 into the fracture 39 of the production well 17 will be avoided.

As the next step, a combustion front extending vertically through the formation 11 along the injection well 16 is provided by any desired mechanisms. For this purpose, it may be desired to provide at least one additional fluid-entry from the injection well 16 into the formation 11 below the level of the fracture 33. The fluid-entry may be perforations through the casing 18 and cement bond 19 similar to the perforations 24 of the production well 17. However, it is preferred that the fluid-entry be provided by at least one, or more, additional horizontal fractures 41 and 42. The fractures 41 and 42 may be provided by any suitable means. The procedure described for producing the fracture 33 may be also used for producing the fractures 41 and 42. It is to be noted that the criterion of spacing the fracture 39, and any other fluid-entry from the well 16, from the fracture 33 is likewise applicable to the fractures 41 and 42. Suitable means are used for initiation of the combustion front in the formation 11 along the injection well 16. Such means may be provided by circulating the combustion-supporting gas into the well 16 via conduit 22 so that the front is supplied by auto-ignition. Usually, some heating means within the injection well 16 will be used for heating the adjacent parts of the formation 11 to ignition temperatures. By these means, a combustion front is provided which extends substantially the vertical thickness of the formation 11 adjacent the injection well 16.

Thereafter, the flow of the combustion-supporting gas is continued into the well 16 and flows through the formation 11 toward the fracture 39 of the production well 17. The combustion front moves cocurrently with the flow of the combustion-supporting gas to produce a heated zone 44. The heated zone 44, denoted by shading in the formation 11, resides at temperatures wherein liquid blocks are avoided and gravity drainage is accelerated. The heated zone 44 is bounded forwardly by an incline which advances at uniform rates vertically and horizontally for moving the viscous hydrocarbons from the formation 11 into the fracture 39. This arrangement prevents a premature breakthrough of the injected combustion-supporting gas from any fluid-entry such as one of the fractures 33, 41, and 42, into the fracture 39. As a result, no substantial amounts of hydrocarbons in the formation 11 are bypassed. Similarly, the combustion-supporting gas flows principally toward the fracture 39. This is of advantage in that the displaced viscous hydrocarbons drain into the fracture 39, and the concurrent gas flow lowers the liquid saturation in the formation 11 adjacent the fracture 39. This functioning prevents liquid blocks from occurring in unheated zones in the formation 11 during the movement of hydrocarbons before the direct combustion front toward the production well 17. Additionally, the fluids produced from the fracture 39 into the well 17 contain both heated gaseous combustion products and liquid hydrocarbons. This combined flow reduces the temperature of the hot gases in the production well 17 to protect it substantially against destruction. Additionally, the particular spacings between the horizontal fractures, or any other fluid-entry, extending between the wells 16 and 17, avoid the direct intercommunications between these fractures. This result provides for the maximum vertical and horizontal coverage of the direct combustion front in its movement away from the injection well 16 before its breakthrough into the production well 17.

Another step is the recovering of fluids containing hydrocarbons from the production well 17 solely from the lower half of the formation 11. These fluids are conveyed through the conduit 29 to the earth's surface for ultimate utilization. The arrangement of the production well 17 is

of especial utility for producing fluids from the formation 11 since simple structures are usable. Fluid flows are easily controlled in the well 17 without sophisticated apparatus for segregating extremely hot combustion gases from liquid hydrocarbons. If it is desired, a liquid level 5 may be maintained in the production well 17 adjacent its lower extremity as a seal. The seal provides for immediate displacement of produced fluids into the conduit 29. This also provides a safer means of operation by avoiding a build-up of explosive gaseous mixtures within the production well 17.

It is intended that the foregoing description be taken in illustration, and not in limitation, of this invention. Various changes and alterations in the described steps 10 may be made without departing from the spirit of this invention. It is intended that such arrangements be considered within the scope of the appended claims; and that these claims define the method of this invention.

What is claimed is:

- 20 1. A method for recovering viscous hydrocarbons from a thick subterranean formation without significant horizontally disposed barriers which limit vertical fluid flows, the steps comprising:
  - (a) providing spaced-apart injection and production well means penetrating into the hydrocarbon-bearing formation for conveying fluids between the earth's surface and said formation;
  - (b) providing in the upper half of said formation a horizontal fracture as a fluid-entry extending from said injection well means substantially across said formation to a position spaced from said production well means a distance in which a reverse combustion front can expand vertically across the upper half of the formation;
  - (c) establishing a combustion front vertically across the upper half of said formation adjacent said production well means, and then moving said front toward said injection well means by passing a combustion-supporting gas from said injection to said production well means until said front extends at least the vertical extent of said upper half of said formation and horizontally to adjacent the terminus of said fracture;
  - (d) removing fluids from said production well means solely at the upper half of said formation;
  - (e) providing a horizontal fracture extending from said production well means toward said injection well means in the lower half of said formation and adjacent its lower bedding plane, said fracture extending horizontally in said formation from said production well means to reside not closer at any location to the first-mentioned fracture extending from said injection well means a distance d less than about three-fourths the thickness of said formation and said horizontal fracture extending from said production well means residing not closer at any location to any fluid-entry location into said formation from said injection well means a distance d' defined by equations (1) and (2):

$$d' = d \quad (1)$$

wherein $K_v = K_h$

$$d' = d \times \frac{K_h}{K_v} \quad (2)$$

wherein $K_h > K_v$

where in the equations K_v is the permeability to fluids in the vertical and K_h is the permeability to fluids in the horizontal in said formation;

- (f) establishing a combustion front extending vertically in said formation along said injection well means and moving said front toward said production well means with a concurrent flow of combustion-supporting gas, and
- (g) recovering fluids containing hydrocarbons from said production well means solely at the lower half of said formation.

2. The method of claim 1 wherein said fracture obtained in step (b) extends from about 50 to 75 percent of the distance between said well means.

3. The method of claim 1 wherein prior to establishing said combustion front in step (f), at least one additional horizontal fracture is provided as a fluid-entry extending from said injection well means toward said production well means and at a lower level than said horizontal fracture obtained in step (b).

4. The method of claim 1 wherein said horizontal fracture obtained in step (b) resides at a level spaced from the upper boundary of said formation one-fourth the thickness thereof, and said horizontal fracture obtained in step (e) resides at a level spaced from the lower boundary of said formation not more than one-fourth the thickness thereof.
